(57) CLAIM

The ornamental design for a needlework accessory holder, as shown and described.

DESCRIPTION

FIG. 1 is a front and left side perspective view of a needlework accessory holder showing my new design. Needles inserted into a cushion of the holder are shown in broken lines and are not part of the design. A removable card with flosses hanging from holes in it is shown in broken lines and is not part of the design;

FIG. 2 is a top plan view thereof;

FIG. 3 is a front elevation view thereof;

FIG. 4 is a right side elevation view thereof;

FIG. 5 is a rear elevation view thereof; and,

FIG. 6 is a bottom plan view thereof.
